JEWELRY BOX

Marvin Wernick, Los Angeles, and Irving H. Plone, Playa Del Rey, Calif., assignors to Republic Corporation, Beverly Hills, Calif., a corporation of California

Filed Oct. 21, 1968, Ser. No. 14,096

Term of patent 14 years

Int. Cl. D9—04

U.S. Cl. D9—238

Fig. 1

Fig. 2

FIG. 1 is a top plan view of a jewelry box showing our new design;

FIG. 2 is a side elevation thereof; and

FIG. 3 is an end elevation thereof.

The side and end opposite those shown in FIGS. 2 and 3 are identical thereto and the bottom is plain and unornamented.

We claim:

The ornamental design for a jewelry box, as shown and described.
